UNITED STATES PATENT OFFICE.

EDWARD F. CHAFFEE, OF SYRACUSE, NEW YORK, ASSIGNOR TO O. M. EDWARDS COMPANY, INC., OF SYRACUSE, NEW YORK, A CORPORATION OF NEW YORK.

RACK FOR WINDOWS.

1,370,948.

Specification of Letters Patent.

Patented Mar. 8, 1921.

Application filed October 28, 1914. Serial No. 869,005.

To all whom it may concern:

Be it known that I, EDWARD F. CHAFFEE, a citizen of the United States, and residing at Syracuse, in the county of Onondaga and 5 State of New York, have invented a certain new and useful Rack for Windows, of which the following is a specification.

This invention has for its object the production of a rack and window stop, which 10 rack and stop are particularly applicable for use in connection with spring operated railway car windows; and it consists in the novel features and in the combinations and constructions hereinafter set forth and 15 claimed.

In describing this invention, reference is had to the accompanying drawings, in which like characters designate corresponding parts in all the views.

20 Figure 1 is a front elevation, partly broken away, of a window provided with a preferable form of this rack.

Fig. 2 is an enlarged inner face view, partly in section, of this rack, the contiguous part of the window sash and catch carried thereby being also shown.

25 Fig. 3 is a fragmentary perspective view of the form of rack shown in the preceding figures.

30 This rack comprises a strip of sheet metal formed with a series of slots and integral loops arranged in the rear of the slots and opposed thereto and joined at their ends to the body of the strip at the ends of the slots, 35 said loops being open at their sides and hence, disconnected from the body of the strip at the sides of the slots.

1 designates the window sash. 2 is the catch which is operated by a suitable 40 handle 3.

4 designates the rack which in this embodiment of my invention is formed on the inner stop of the window frame.

The rack is, in this form of my invention, 45 shown as provided on a strip of sheet metal which is bent in the form of a channel. As here shown, said strip is shaped to form two channels 5, 6 facing in opposite directions, the walls of the channel 5 forming the body 50 of the stop, and the channel 6 being a guide for the window curtain.

The rack is provided in one of the sides of 55 the channel 5, that is, the side 7 opposed to the front face of the window sash 1, the side 7 being formed with a plurality of slots

8 and loops 9 in the rear of the body or intact portion of the side 7. The loops 9 are connected at corresponding ends to the body or intact portion of the side 7 at the ends of the slots. Usually all of the loops 60 with the exception of the lower one, are connected at their opposite ends at the ends of the slots. The loops 9 which are joined at both ends to the body of the strip are formed with inclined faces 10 and abrupt 65 faces 11, the inclined faces constituting ratcheting surfaces for the nose 12 of the catch 2 when the window is being raised, and the abrupt surfaces 11 forming shoulders for engaging the end of the catch 2 70 to hold the window from falling by its own weight to its closed position.

The loop 9, associated with the lowermost slot 8, is connected at its lower end only to the body or intact portion of the side 7 and 75 is disconnected therefrom at its upper end so that the upper end of the lowermost slot forms an abrupt shoulder for engaging the nose 12 of the catch 2 in order to lock the window sash 1 in its closed position.

80 This rack is formed by providing a strip of sheet metal, that is, the side 7 with the series of parallel slits and indenting or stretching inwardly the portion of the metal between the slits.

85 What I claim is:—

1. The combination of a window frame, a sash movable in the frame, a catch associated with the window, a rack associated with the frame and arranged to be engaged 90 by the catch, the rack comprising a strip of sheet metal having a series of slots spaced apart and loops opposed to the slots and connected at their ends to the body of the strip at opposite ends of the slots and separated at the side edges from the body of the strip, the end portions of the loops being arranged to be engaged by the catch and thus relieve the end walls of the slots, substantially as and for the purpose described. 100

2. A rack for windows comprising a strip of sheet metal formed with a series of slots spaced apart, and loops opposed to the slots and connected to the body of the strip at the opposite ends of the slots, the loops being 105 open at their sides and hence disconnected from the body of the strip at the sides of the slots, and being provided at their opposite ends with inclined and abrupt portions, substantially as and for the purpose specified. 110

3. A window stop comprising a sheet metal strip bent in the form of a channel, one of the walls of the channel being formed with a series of slots and loops connecting the ends of the slots, the loops projecting into the channel, substantially as and for the purpose set forth.
4. The combination of a window frame, a sash movably mounted in the frame, a window stop arranged to engage one of the faces of the sash at the margin thereof and comprising a strip of sheet metal in the form of a channel and arranged with the outer face of one of the walls of the channel opposed to the margin of the sash, said wall being formed with a series of openings therein and integral loops offset from the openings and projecting into the channel and joining at their ends the main part of said wall at the ends of the openings, each loop having inclined and abrupt portions at their opposite ends, and a catch mounted on the sash and coacting with the openings and the inclined and abrupt portions of said loops, substantially as and for the purpose specified.
5. The combination of a window frame, a sash movably mounted in the frame, a

window stop arranged to engage one of the faces of the sash at the margin thereof and comprising a strip of sheet metal in the form of a channel arranged with the outer face of one of the walls of the channel opposed to the margin of the sash, said wall being formed with a series of openings therein and integral loops offset from the openings and projecting into the channel and joining at their ends the main part of said wall at the ends of the openings, each loop having inclined and abrupt portions at their opposite ends, and a catch mounted on the sash and coacting with the openings and the inclined and abrupt portions of said loops, substantially as and for the purpose specified.

In testimony whereof, I have hereunto signed my name in the presence of two attesting witnesses, at Syracuse, in the county of Onondaga, and State of New York, this 16th day of September, 1914.

EDWARD F. CHAFFEE.
